(57) **CLAIM**

The ornamental design for a fluorometer display screen, as shown and described.

DESCRIPTION

FIG. 1 is a front view of a first embodiment of a fluorometer display screen of our new design; and,

FIG. 2 is a front view of a second embodiment of a fluorometer display screen of our new design.

The portions of the display screen, features, and text depicted in broken lines are not part of the claimed design.
